IMPROVEMENT IN SEWING-MACHINES.

T. K. REED, OF EAST BRIDGEWATER, MASSACHUSETTS.

Letters Patent No. 60,241, dated December 4, 1866.

SPECIFICATION.

TO ALL WHOM IT MAY CONCERN:

Be it known that I, T. K. REED, of East Bridgewater, in the county of Plymouth, and State of Massachusetts, have invented an Improvement in Sewing-Machines; and I do hereby declare that the following, taken in connection with the drawings which accompany and form part of this specification, is a description of my invention sufficient to enable those skilled in the art to practise it.

In all sewing-machines in which shuttles are used, more or less difficulty occurs in adjusting the tension upon the shuttle-thread. So far as I know, in all such machines, the shuttle has to be removed or taken from the machine every time the tension of its thread is to be changed; and as every removal breaks the thread, and thereby weakens the stitch, and as, generally, the tension is brought to proper adjustment only by repeated trials, it is an important desideratum to be able to manipulate the tension device without removing the shuttle, and still more important to be able to effect the adjustment while the machine is running. To effect these results is the object of my invention, which, broadly stated, is to combine with the tension device of a sewing-machine shuttle and the coöperative stitch-forming mechanism, a mechanism operated from the outside of the sewing-machine framework or table, to actuate the tension device while the machine is running, and to thereby adjust or increase or diminish the tension upon the shuttle-thread, as circumstances may require.

The drawings represent so much of the mechanism of a Florence sewing-machine as will enable my invention, shown as applied thereto, to be clearly understood—

A, showing a plan of the shuttle-race and mechanism adjacent thereto.

B, a section on the red line shown in A.

C, a view of the open side of the shuttle.

a denotes the shuttle-containing case, the top plate of which (not represented in the drawings) forms the work-supporting surface. As the feed and stitch-forming mechanism are not at all changed, so far as relates to feeding the work and forming the stitches, the needle, presser-foot, and feeding-device are omitted from the drawings, in order to show more prominently the mechanism for carrying out my invention. b denotes the shuttle-race; c the shuttle; d, the bobbin thereof; e, the hinged tension-plate, stress upon which, to create pressure upon the bobbin-thread, is exerted by a "C spring," f, one end of which is hooked into an arm extending from the tension-plate, while the other end has a nut or screw-thread formed in it, into which a screw-thread or shaft, g, works. The tension-plate is hung in bearings in the shuttle, and the arm to which the spring is applied extending down below one of the bearings, the pressure of the spring forces the plate against the thread and makes the tension. By turning the screw-shaft g, and thereby cramping the spring f, more or less, this pressure is increased or diminished, as may be desirable. As usually applied, this shaft has a recessed head on one end for application of a screw-driver, and to regulate the tension, the shuttle is removed, and the screw turned to adjust the stress of the tension-spring. I apply to the screw-shaft a small spur-wheel or pinion, h, by turning which the screw is turned, and the spring cramped more or less, in accordance with the direction h, by which the wheel is rotated. A groove, i, is formed at each end of the shuttle, in the plane of the wheel, as seen at C. Through the side wall k, of the shuttle-race, two holes, l, are made in the horizontal plane of the wheel h, and through these holes the inner ends of two slide-rods, m, work, their outer ends extending beyond the outer side of the box or casing a, as seen at A. The inner end of each of these slides m is formed with spur-teeth n, and each has a spring, o, applied to it, the tendency of which is to carry the slide into the position shown in section at A, (this fragmentary section being taken in the line of the spur-wheel h.) The extent of the inward movement of the slide is limited by a shoulder, p, which brings up against the face of the shuttle-race. When in this position, the teeth on the slide project into the path of the teeth of the spur-wheel, so that as the shuttle flies in the direction denoted by the arrow thereon, the teeth on the slide will strike the wheel, and slightly rotate it, and thus cramp up the spring and increase the tension. The section at A shows the spur-wheel as having been operated upon by the slide, and as having gone beyond it, and before the rod is returned to its normal position, which return takes place during the continued movement of the shuttle in the same direction, or before the spur-wheel again comes opposite to the slide, in its return movement. When the other slide is forced in by its spring, the spur-wheel is struck by the spur on the end of said slide, as the shuttle flies in the opposite direction, and the tension-spring shaft is thereby so turned as to lessen the stress upon the spring, and diminish the tension on the thread, the slide being carried back before the spur-wheel again comes opposite thereto. Each slide has a spring-latch, q, (see the section D,) by which it is latched in

normal position, the latch locking against the case of the facing *a*. By depressing the latch with the hand, either rod will be carried in at the proper time, by its spring, as will be readily understood. This proper time, and the throwing the spur of each rod out of the path of the spur-wheel, after each engagement, is determined and regulated as follows: each slide, adjacent to the wall of the shuttle-race, has a projection or friction-roll, *r*, on its lower surface, and just below these rolls or projections is a sliding-plate, *s*, having two projections, *t*, this plate being hung on two pins, *u*, and having a reciprocating endwise movement imparted to it by the shuttle-driver *v*. This plate bears two inclines, *w*, which act upon the rolls or projections whenever either slide *m* has been pressed into the path of the spur-wheel. This action of the incline takes place immediately after the action of the spur of either slide *m* upon the spur-wheel on the tension-spring shaft, or just at the end of the motion of the shuttle, in either direction, the incline acting upon the roll or projection, and driving back the slide, the latch at the outer end of which springs down and locks the slide in normal position. In this normal position, the inclines pass between each roll or projection and the outer wall of the shuttle-race, without striking or affecting the position of either slide. It will thus be seen that, no matter how fast the machine may be running, the tension upon the shuttle-thread may be regulated or varied, at pleasure, without removing the shuttle or stopping the machine, and that the tension is increased or diminished according to the rod manipulated. By freeing the latch on either rod after each motion of the shuttle, the tension-regulating screw may be turned to any extent required. It will be obvious that this mechanism may be greatly varied for different styles of machines or shuttles, or in the same machine, many modifications having occurred to myself; but with this style of machine, I consider the mechanism shown to be as reliable and effective as any. In a shuttle like that shown at *E*, a modification will be necessary, which will drive the plate *x*, (between which and the shuttle-face the thread passes,) more or less in one direction or the other, as the tension is to be increased or diminished.

I claim combining with the reciprocating shuttle and shuttle-race of a sewing-machine, a device or mechanism, operated by the movement of the shuttle to regulate or change the tension of the shuttle-thread, substantially as set forth.
